Attorneys.

UNITED STATES PATENT OFFICE.

PERCIVAL TAYLOR, OF BOLTON, ENGLAND, ASSIGNOR OF ONE-HALF TO JABEZ JOHNSON HODGKINSON AND PEARSON LIMITED, OF MANCHESTER, LANCAS TER, ENGLAND.

TERRY OR LOOPED FABRIC.

1,398,752.

Specification of Letters Patent.

Patented Nov. 29, 1921.

Application filed March 31, 1919. Serial No. 286,314.

To all whom it may concern:

Be it known that I, PERCIVAL TAYLOR, a subject of the King of Great Britain, and resident of Bolton, in the county of Lancashire, England, have invented a certain new and useful Improvement in Terry or Looped Fabrics, of which the following description, having reference to the accompanying sheets of drawings, is a specification.

10 In the production of terry or looped fabrics of the type or class which have their loops or terry formed by the reed beating up the weft to different positions (a system of weaving which is well understood) one 15 of the difficulties encountered is to have the terry warps or loops so bound into the body of the fabric that they will retain their positions firmly. Many methods of shedding or treadling the threads of warp and many 20 kinds of warp threads and the treatment of same have been used and followed to attain the object desired, however according to my present invention I so interweave the terry warp threads with the weft threads 25 that these latter interlock with the former in such a manner that any pull on the terry or loop warp threads tends to cause same to grip certain of the weft threads more firmly between them, thus a pull on the terry warp 30 cannot so readily draw out the loops which are now held and locked in a fixed position, while the order of shedding which I follow is such as to give a distinctive appearance to the resultant fabric and one that enhances 35 its commercial value.

In order that my said invention may be readily understood, I have hereunto appended a sheet of drawings illustrative of the method in which the threads of warp are 40 operated and the order in which such operations are carried out.

Figure 1 is a diagram illustrating two threads of warp and the order in which same pass over and under the threads of weft, to form the ground of the fabric.

Fig. 2 is a similar diagram to illustrate four threads of warp as being interwoven with the weft to form the pile or terry part of the fabric.

50 Fig. 3 is a plan showing the order of treadling the threads of warp.

Fig. 4 illustrates the drawing in plan or the order in which the threads of warp are passed through the healds.

55 In Figs. 3 and 4 the heald shafts are rep-

resented by the lines 1, 2, 3, 4, 5, and 6, while the pile or terry warp threads are represented by the lines *a*, *a*¹ and *b*, *b*¹, and the ground warp threads by the lines *c*, *c*¹ and *d*, *d*¹.

The shots of weft are represented in Figs. 1 and 2 by the blackened circles *g*.

In accordance with my invention (with the modifications hereinafter described) I arrange the terry warp threads *a*, *a*¹ and *b*, *b*¹ to be in pairs, that is to say, where a single terry warp thread has been heretofore used I now use two of such warp threads and I arrange one pair *a* and *b* to form the loops *f* on one side of the fabric at one time 60 while the adjoining pairs *a*¹ and *b*¹ form the loops *f*¹ on the other side thereof at the same time, said order being alternatively reversed. In conjunction with this arrangement of terry warp threads, I use a warp weaving 65 ground with four threads *c*, *c*¹ and *d*, *d*¹ for each four threads of the terry warp threads. The warp threads are drawn through the healds by the first pair of terry threads *a* *b* being taken through the first and second 70 healds as shown by Fig. 4, the adjoining threads of ground warp *c*, *c*¹ are taken through the 5th and 6th healds, the next pair of terry threads are *a*¹, *b*¹ are taken through the 3rd and 4th healds while the 75 two remaining ground warp threads next succeeding are again taken through the 5th and 6th healds.

The order of treadling or shedding as 80 shown by Fig. 3 of the drawings is plain 85 for four picks by the ground shafts 5 and 6. The shaft 5 then remains down for two picks and the shaft 6 remains up for two picks. The next four picks are plain while during the next two picks the shaft 5 is up 90 and the shaft 6 is down for both picks, the shafts which are raised being shown by crosses on the shafts 5 and 6 Fig. 3.

The crosses shown on the shafts, 1, 2, 3 and 4 show which shafts are raised, while 100 the absence of such crosses shows where the shafts are down. As will be observed one of the pile threads will pass over or under three shots of weft *g* at one time while its neighboring pile thread will pass over or under 105 only two shots, hence when these threads are beaten up to form the pile or loop, the thread which has passed over or under these picks will have a broader base than has the thread that has only passed over or under two picks 110

hence it is slightly shorter or does not extend as far from the body of the fabric.

This formation of longer and shorter loops adjoining each other gives the resultant fabric a distinctive appearance not otherwise attainable.

As a modification of the weave hereinbefore described, I may make use of terry warp threads arranged in groups or series 10 of three, four or more threads adjoining each other, that is to say, when I use three threads I shall have two threads *a* with a thread *b* arranged between them and when I use four threads then I shall have one 15 thread *a* adjoined by a thread *b* which has on the other side of it another thread *a* which again is adjoined by a thread *b*, these orders of arrangement of the threads *a* and *b* being repeated as greater numbers are used. 20 When I employ said arrangements of threads I may break the treading of them so that they are split up into (as near as possible) a plain weave before and after (or between) their loop formations so as to produce, by 25 the treading of these terry threads and the treading of the ground warp threads, a plain weave or one as nearly plain as is possible entirely around each pair or bunch of loops.

By arranging the terry threads to adjoin 30 each other in pairs (or in other numbers) and treading all the warp threads so that each pair or bunch of loops is surrounded by a weave as nearly as possible "plain" I find that the loop or terry warp threads are firmly 35 held since any pull on any pair or bunch of pile threads will cause the thread encircling the extra pick of weft to press said weft against the next pile thread and so lock it in position in such a way that the greater the 40 pull the firmer they grip the weft and consequently the firmer will the loops be secured.

The fabric produced, as hereinbefore described, may be woven in a common one 45 shuttle terry loom, but I have found that the order of treading is such that on using two kinds of weft with those threads which are gripped by the terry warp being of a thicker, thinner or otherwise different character from the other threads, a further distinctive 50 and novel appearance is given to the resultant fabric.

It is obvious that where more than one

kind of weft is used, the loom will have to have a correspondingly increased number of shuttles.

Such being the nature and object of my said invention, what I claim is:—

1. A terry-fabric composed of terry warp threads arranged in pairs, one thread of one pair being made to take over two threads of 60 weft over which it forms a loop, the other thread of said pair taking over three threads of weft also to form a loop, while the two threads of the pair of terry warp threads adjoining the former pair are arranged so 65 that one of this secondary pair of threads takes under two threads of weft to form a loop and the other of said second pair of threads takes under three threads of weft, also to form a loop, thus forming terry-loops 70 of two sizes on both sides of the fabric.

2. A terry fabric composed of terry warp threads arranged in sets of three, two of the threads in each set being arranged to take over two threads of weft to form loops, the 75 other thread in the same set being made to take over three threads of weft over which they also form loops, while the sets of terry threads adjoining the former set are arranged so that one of them takes under two 80 threads of weft to form loops, the remaining two threads in the same set being made to take under three threads of weft to form loops, said resultant loops being of two sizes on both sides of the fabric.

3. In the production of a terry-fabric composed of terry warp threads arranged in pairs one thread of one pair being made to take over two threads of weft over which it forms a loop, the other thread of said pair taking over three threads of weft also to form a loop and one of the second pair of threads takes under three threads of weft 90 while the other thread of said second pair of threads takes under two threads of weft, 95 thus forming terry loops of two sizes on both sides of the fabric, the employment of warp threads which are interwoven with the loop threads in the order of a plain weave, (that is one thread up and one thread down) between the loops except in the case of one part only where the threads are taken over and under two threads of weft.

PERCIVAL TAYLOR.
